Primary Examiner — Omeed Agilee

CLAIM

The ornamental design for an instrument and utensil for medical or laboratory diagnosis, as shown and described.

DESCRIPTION

1. Instrument and utensil for medical or laboratory diagnosis
5. Instrument and utensil for medical or laboratory diagnosis

1.1 : Perspective

1.2 : Perspective

1.3 : Front

1.4 : Back

1.5 : Left

1.6 : Top

1.7 : Bottom

5.1 : Perspective

5.2 : Perspective

5.3 : Front

5.4 : Back

(Continued)

5.5 : Left

5.6 : Top

5.7 : Bottom

1 Claim, 14 Drawing Sheets
